UNITED STATES PATENT OFFICE

164,079

RADIO-PHONOGRAPH AND TELEVISION CABINET

Samuel E. Adler, Chicago, Ill., assignor to Admiral Corporation, Chicago, Ill., a corporation of Delaware

Application June 24, 1950, Serial No. 10,742

Term of patent 14 years

(Cl. D56—4)

To all whom it may concern:

Be it known that I, Samuel E. Adler, a citizen of the United States, residing at Chicago, in the county of Cook, State of Illinois, have invented a new, original, and ornamental Design for a Radio-Phonograph and Television Cabinet, of which the following is a specification, reference being had to the accompanying drawing, forming part thereof.

Fig. 1 is a front perspective view of the front, left side and top panels of a radio-phonograph and television cabinet, showing my new design, the two upper doors thereof being open; and

Fig. 2 is a front elevational view thereof, the upper doors being closed and the lower door in open position.

The dominant features of my new design reside in that portion shown in full lines of the drawing.

The opposite side is the same as the side shown and the back is plain.

I claim:

The ornamental design for a radio-phonograph and television cabinet, as shown and described.

SAMUEL E. ADLER.
